UNITED STATES PATENT OFFICE.

ARNOLD PFAU, JR., OF MILWAUKEE, WISCONSIN.

DESIGN FOR AN ELECTRICAL HEATING APPLIANCE.

Application filed January 10, 1927. Serial No. 20,323. Term of patent 7 years.

To all whom it may concern:

Be it known that I, ARNOLD PFAU, Jr., a citizen of the United States, residing at Milwaukee, in the county of Milwaukee and State of Wisconsin, has invented a new, original, and ornamental Design for Electrical Heating Appliances, of which the following is a specification, reference being had to the accompanying drawing, forming a part thereof.

In the drawings:

Fig. 1 is a view in front elevation of an electrical heating appliance showing my new design.

Fig. 2 is a view in side elevation of the electrical heating appliance of Fig. 1.

I claim—

The ornamental design for an electrical heating appliance, as shown.

In witness whereof, I affix my signature hereto.

ARNOLD PFAU, JR.
